UNITED STATES PATENT OFFICE

2,386,001

SYRINGE

Frank S. Parrigin, Louisville, Ky.

Application July 26, 1943, Serial No. 496,197

1 Claim. (Cl. 128—241)

This invention relates to new and useful improvements in syringes and more particularly to a vaginal douche syringe.

The present invention is an improvement on the patent to J. W. Brunette, No. 1,751,507, issued March 25, 1930.

The principal object of the present invention is to provide a syringe having drain-off means and a liquid escape guard, wherein the guard functions much more satisfactorily than the corresponding feature of the above-named patent.

Another important object of the invention is to provide a syringe of the character stated which can be used with more comfort and effectiveness than devices heretofore known.

Other objects and advantages of the invention will become apparent to the reader of the following description.

In the drawings:

Figure 1 represents a side elevational view of 20 the syringe.

Figure 2 is a top plan view.

Figure 3 is a vertical sectional view.

Figure 4 is a section on the line 4—4 of Figure 1.

Figure 5 is a section on the line 5—5 of Figure 1.

Figure 6 is a fragmentary vertical sectional view showing a modified form of the invention.

Referring to the drawings wherein like numerals designate like parts, it can be seen in Figure 1 that numeral 5 denotes a circular body which serves as a shield or guard against the escape of douche fluid. This may be of hard rubber, and has imbedded therein the flanged end 6 of a hollow fitting 7, which at its lower end, as shown in Figure 3, has a hose attachable nipple 8.

A tube 9 extends upwardly in the fitting 7 and spacially with respect to the side thereof, and at its lower end has a laterally disposed extension merging with the side wall of the fitting 7, and outwardly from this portion of the side wall extends a hose attachable nipple 10.

Projecting upwardly from the guard body 5 is an elongated nozzle 11 having a gradually tapering head 12 in which discharge openings 13 are located. Additional discharge openings 14 are located just short of the head 12, while at the point of the nozzle 11 where it connects with the guard body 5, the nozzle bulges as at 15 and has therein formed slots 16, communicating the outside of the nozzle 11 with the interior of the bulged portion 15 as well as with the interior of the fitting 7.

It can here be seen that a passageway 17 is formed longitudinally in the nozzle 11 and this passageway terminates at a seat 18 at the lower portion of the nozzle and with it engages the beveled upper end portion of the tube 9.

A trough 19 is formed in the guard body 5 immediately adjacent the slotted portion of the bulge 15 and outwardly from this trough the guard body gradually slopes on a concave to its periphery as denoted by reference character 20.

It can now be seen that douching liquid enters the nipple 10 by way of a hose (not shown), flows through the tube 9 and nozzle 11, and after performing its cleansing operation flows back along the outside of the nozzle 11 and is caught by the trough 19 and to an extent guided by the concaved formation of the top side of the guard body 5. The fluid enters the fitting 7 by way of the slots 16 and passes through a drain tube 15 attached to the nipple 8.

Figure 6 shows a slightly modified form of the invention in that the nozzle 11a is constructed of hard rubber or like material, this nozzle having a bulged portion 15a, the slots 16a, and a guard body 5a having a trough 19a. In carrying out this form of the invention, the guard body 5a has a short neck 22 flanged as at 23. A fitting 7a is provided and accommodates a tube 9a and a nipple 10a and this fitting 7a is flanged at its upper portion as at 24. A suitable annular clip or detent 25 is used to bridge the flanges 23, 24, and between these flanged portions of the two sections a suitable gasket 26 may be interposed.

While the foregoing specification sets forth the invention in specific terms, it is to be understood that numerous changes in the shape, size, and materials may be resorted to without departing from the spirit and scope of the invention as claimed hereinafter.

Having described the invention, what is claimed as new is:

In a device of the character described, an elongated, hollow nozzle provided with a head having discharge openings therein, an enlarged portion adjacent the base of said nozzle having a plurality of slots therein, a liquid escape guard body having a groove therein adjacent said enlarged portion of said nozzle, a relatively rigid fitting comprised of a pair of concentric tubular portions secured to the guard body, said inner tubular portion extending beyond said guard body into said enlarged portion of said nozzle and engaging in the hollow portion of said nozzle, said inner tubular portion being provided at its further end with an elbow and a portion extending through the wall of the outer tubular portion, a nipple on the outer end of said inner tubular portion, said outer tubular portion terminating in a second nipple, whereby said inner portion and said hollow nozzle form an inlet, and said slots and said outer tubular portion form an outlet.

FRANK S. PARRIGIN.
